CLAIM

The ornamental design for a drinking bottle, as shown and described.

DESCRIPTION

FIG. 1 is a perspective view of a drinking bottle, according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view of our new design for a drinking bottle shown with lid in an open position for clarity of disclosure; and,

FIG. 9 is an exploded perspective view thereof, shown with the top removed for clarity of disclosure.

The broken lines in the drawings illustrate portions of the drinking bottle that form no part of the claimed design.

1 Claim, 9 Drawing Sheets
